UNITED STATES PATENT OFFICE.

JOHN SHEPHERD, OF MACON, MISSOURI.

CAR-VENTILATION.

SPECIFICATION forming part of Letters Patent No. 251,957, dated January 3, 1882.

Application filed September 29, 1881. (No model.)

To all whom it may concern:

Be it known that I, JOHN SHEPHERD, a citizen of the United States of America, residing at Macon, in the county of Macon and State of Missouri, have invented certain new and useful Improvements in Car-Ventilators; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification, and in which—

15 Figure 1 is a side view of my improved cooling apparatus for passenger-cars, and Fig. 2 is a longitudinal section of the same. Fig. 3 is a detail plan view, showing conducting-tubes and ventilating-orifices.

20 This invention relates to an improvement in air-cooling apparatus for passenger-cars, it being designed to collect and utilize air for cooling the apartments; and it consists of a flared-mouth tube connected to a condensing fan and pipe composed of sections, each section under a car having a supplemental fan or exhaust to supply the car with air, substantially as hereinafter more fully set forth and claimed.

In carrying out my invention I employ a 25 condensing rotary fan, A, whose cage A' may, by preference, be located upon the front of the locomotive as the most eligible position to collect or receive the air. To this cage or drum is supplied a flared-mouthed tube, B, which collects and conducts into the cage against the fan A the air produced by the cars in motion. The inrushing air will revolve and cause the

fan to condense the air, which is taken therefrom through sections of pipe C C and discharged into supplemental cages and in contact with supplemental fans or exhausting devices D, arranged one under each car of the train. The sections of hose or pipe are capable of conforming to the vibrations of the cars. The fans D exhaust the air into the cars at suitable 40 points through upright tubes d' connecting with the cages of the said fans and the car-apartments. Each fan D is supported upon a shaft, a, which is driven by a belt, b, encompassing a pulley, c, upon the car-axle, and a pulley, d, 45 upon said shaft a to operate or revolve the fan.

The fans D may be located within the cars, which is the preferred way.

The locomotive-tender pipe-section is designed to be passed through the water-chamber thereof, in order to reduce the temperature 50 of, and thus cool, the air.

The pipe-sections under the cars are designed to be passed through ice or refrigerant chambers located thereunder to further cool 55 the air, or rather the supply of air for each car.

Having thus fully described my invention, I claim and desire to secure by Letters Patent—

The combination, with the fan A, of pipe C, and supplemental fan D, having the pipes d' 60 leading into the car, substantially as and for the purpose set forth.

In testimony whereof I affix my signature in presence of two witnesses.

JOHN SHEPHERD.
